GAS HEATING STOVE

Filed May 9, 1928

Earl M. Brandt,

INVENTOR

BY *Victor J. Evans*

ATTORNEY

UNITED STATES PATENT OFFICE.

EARL M. BRANDT, OF IRONTON, OHIO.

GAS HEATING STOVE.

Application filed May 9, 1928. Serial No. 276,446.

This invention relates to stoves primarily adapted to be heated by gas and other fuels.

An object of the invention contemplates a base member having openings adapted to 5 permit the passage of air within the stove.

Another object of the invention comprehends a fire pot carried by the base member and adapted to convey the air passing upwardly through the openings in the base 10 member.

A further object of the invention embodies a burner carried within the fire pot and having orifices disposed in spaced relation to the walls of the fire pot to permit mixing 15 and combustion of the fuel with the air.

More specifically stated the fire pot is provided with a band upon its upper end to serve as an extension therefor which will prevent flames from coming in direct contact with the sides of the stove. 20

With the above and other objects in view, the invention further includes the following novel features and details of construction, to be hereinafter more fully described, illustrated in the accompanying drawings and 25 pointed out in the appended claim.

In the drawing:

Figure 1 is a perspective view of the invention, partly broken away to illustrate the 30 construction thereof.

Figure 2 is a longitudinal sectional view taken through the invention.

Figure 3 is a transverse sectional view taken on line 3—3 of Figure 2.

Referring to the drawing in detail, wherein like characters of reference denote corresponding parts, the reference character 10 indicates a base member having a downturned 35 peripheral edge 11 and to the underside of which are connected supporting legs 12. An annular channel 13 within the upper side of the base member 10 is adapted to receive and support the legs depending from the bottom or peripheral edges of a stove body 14.

Openings 15 of a configuration desired, within the base member 10, are disposed in a circular course within the annular circular channel, the purpose of which will be presently apparent.

A fire pot 16 of inverted frusto-conical shape is provided with depending legs 17

adapted to engage the upper side of the base member 10 to provide an air space therebetween whereby air passing upwardly through the openings 15 in the base member 55 10 may follow in and be directed through air space beneath the bottom edge of the fire pot. Ribs 18 carried upon the upper side of the base member 10 are adapted to engage the legs 17 of the fire pot 16 to prevent independent movement of the latter, whereby the heat will be equally distributed circumferentially of the stove body 14.

An annular flange 19, provided upon the upper periphery of the fire pot 16, has cut-out portions 20 adapted to receive depending ears 21 upon the lower peripheral edge of a band or reflector plate 22. Said plate 60 also provides an extension for the fire box.

A burner in the nature of a hollow disk 70 member 23 provided with openings 24 upon the outer marginal edge, and passing upwardly through the base member and fire box will produce a highly expansible gas of high temperature and which will be equally 75 distributed upon the stove body incident to the relative arrangement of the base member, fire pot, burner and band or reflector plate.

After the burner has been called into use 80 for a prescribed time, the plate 22 will reflect heat downwardly upon the burner and transform the gas into a highly expansible state.

As shown, the orifices in the burner are elongated or oblong to spread the flame toward the adjacent orifices whereby a circular flame will pass upwardly within the fire pot to evenly heat all sides of the stove body. 85

The invention is susceptible of various changes in its form, proportions and minor 90 details of construction, and the right is herein reserved to make such changes as properly fall within the scope of the appended claim.

Having described the invention, what is claimed is:

A stove comprising a base plate having an annular channel within the upper side thereof adapted to accommodate the bottom edge of a stove body, said base plate having openings disposed in a circular course within 100 said channel, a fire pot having depending legs upon the lowermost portion thereof to

support the lower periphery of the pot in spaced relation to the upper side of the base plate and adjacent the openings therein, the fire pot being outwardly and upwardly flared, and a burner of hollow disk like formation having orifices within the peripheral edge thereof being arranged within the fire

pot in spaced relation to the inner side wall of the fire pot to facilitate mixing and combustion of the fuel emitted therethrough with the air passing upwardly within the fire pot.

In testimony whereof I affix my signature.
EARL M. BRANDT.
